PIPE WRAPPING MACHINE

Leland S. Rosener, San Francisco, Calif., assignor
to The Paraffine Companies, Inc., San Fran-
cisco, Calif., a corporation of Delaware

Application April 12, 1927, Serial No. 183,081

53 Claims. (Cl. 242—11)

My invention relates to a machine for wrapping objects, and one of the objects of the machine is to provide means for wrapping a protective strip of material about the pipe comprising a pipe line already in position in the ground.

Another object of the invention is the provision of a pipe wrapping machine by which protective strips are wrapped about a fixed pipe, and embodying means for applying an adhesive and waterproof fluid to the pipe and wrapping to hold the latter in place and seal the pipe with an impervious covering which is water and decay proof.

Another object of the invention is the provision of improved means for holding the supply roll of wrapping material during the operation of the machine.

My invention possesses many other objects and valuable features, some of which will be set forth in the following description of my invention which is illustrated in the drawings forming part of the specification. It is to be understood that I do not limit myself to the showing made by the said description and drawings, as I may adopt varying forms of my invention within the scope of the claims.

Referring to the drawings:

Figure 1 is a plan view showing the wrapping machine of my invention in position for applying a wrapping strip on a pipe line; and Figure 2 is a side elevation of the same.

Figure 3 is an end elevation of the machine, the view being taken in the direction of the arrow 3 of Figure 2.

Figure 4 is a sectional view showing the driving gear for the reel and distributor head. The plane of section is indicated by the line 4—4 of Figure 2.

Figure 5 is a transverse sectional view thru the adhesive fluid distributor head, the plane of section being indicated by the line 5—5 of Figure 2.

Figure 6 is a longitudinal sectional view thru the upper part of the distributor shown in Figure 5. The plane of section is shown by the line 6—6 of Figure 5.

Figure 7 is a sectional view of the secondary strip reel. Line 7—7 in Figure 2 indicates the plane in which the view is taken.

Figure 8 is a transverse sectional view thru the main wrapping strip reel. The plane of section is indicated by the line 8—8 of Figure 2.

Figure 9 is a sectional view taken in a vertical plane coincident with the axis of the reel shown in Figure 8. The plane of section is indicated by the line 9—9 of Figure 8.

In broadly descriptive terms, the wrapping ma-

chine of my invention comprises a frame, provided with means for supporting it upon the pipe to be wrapped. A reel on which a quantity of the wrapping material is held in a roll encircling the pipe is arranged on the frame, and a secondary reel carrying an additional quantity of wrapping material is mounted with the first reel for orbital rotation about the pipe. Means are provided for rotating the reels to wind the strips about the pipe and simultaneously to advance the frame along the pipe so that the wrapping strips are applied to the pipe spirally one over the other. Means are also provided for applying a sealing fluid such as hot asphalt between the pipe and the wrapping material, so that the wrapping strips are adhesively retained in place and the laps sealed with an adhesive, waterproof and durable material.

In greater detail, the wrapping machine of my invention comprises a frame 2, provided with rollers 3, for supporting the frame on the pipe 4 which is to be wrapped. Shoes 6 supported on the frame on each side of the pipe prevent lateral displacement of the frame. Extending laterally from the frame is an arm 7 carrying a wheel 8 adapted to rest on a plank 9 temporarily arranged at the side of the ditch in which is the pipe line. In order to use our machine to wrap a pipe line already installed, it is necessary to uncover the pipe by means of ditching around it and in doing this, the dirt may be leveled off on one side so as to provide an approximately true surface 11 on which the planks 9 may be conveniently laid. The mechanism may thus travel along the pipe without danger of tipping over.

Journaled in suitable bearings 12 in the frame 2 is a shaft 13 driven by the gears 14 from the motor 16 connected by flexible conductors with any suitable source of power. Splined on the shaft 13, and movable therewith by means of the handle 17 is a friction wheel 18 adapted to engage the face of the friction disk 19 arranged on the shaft 21 and pressed by the spring 22 into engagement with the friction wheel. The shaft 21 is also connected by gears 23, shaft 24 and gears 26 with a shaft 27 on which a drum 28 is journaled. A clutch 29 controlled by the handle 31 provides means for coupling the shaft 27 to the drum.

Wound about the drum is a cable 32 one end of which is adapted to be secured to any convenient fixed object in advance of the frame of the machine, and rotation of the drum therefore effects the movement of the machine along the pipe line. The speed of this movement relative to the speed of the main shaft 13 is adjustably controlled by 55

moving the friction wheel across the face of the friction disk.

Fixed on the main shaft 13 is a pinion 33 in mesh with the annular gear or rotor 34, arranged 5 in a bearing 36 which as shown in Figure 4 extends around the upper two-thirds of the journal 37 of the gear, thus leaving a gap in the lower portion of the bearing. The rotor is provided with a removable segment 34a so that when the 10 segment is taken out of the rotor, the machine may be let down over the pipe. With the securing of the segment once more in place by means of the screws 38, the rotor surrounds or encircles the pipe.

15 Extending from diametrically opposite points on the rotor are arms 39 on the ends of which is pivotally mounted a reel frame comprising the side members 41 and the annular plates 42. Journaled in the annular plates 42 are a series of circumferentially spaced rollers 43 each of which is provided with an annularly grooved hub 44 on each side. These annularly grooved hubs provide a journal for the annular plates 46 which comprise rotary flanges for the rollers. In order 20 to permit the assembly of the reel over the pipe line, the annular plates 42 and 46 are also made in two portions as shown best in Figures 3 and 9, and each is adapted to be secured together by the 25 swing screws 47 locked in lugs 48 by the wing nuts 49.

30 The reel thus formed is adapted to hold a roll 51 of wrapping material or strip 52 and because of the friction reducing effect of the rollers 43, this roll may be unwound from the inside as the 35 strip is applied to the pipe. Means are provided for adjusting the angular relation of the reel to the pipe and this is accomplished by providing the end of one of the arms 39 with an upturned end 53 which has pivotally mounted therein a lug 54 thru which is threaded a spindle 56, passing 40 loosely thru a lug 57 on the frame 41 and prevented from axial movement in the lug 57 by the round faced collars 58. A hand wheel 59 permits rotation of the spindle to fix the angular position 45 of the reel.

When the reel is arranged with its axis coincident with the axis of the pipe, it is in position to receive its load of wrapping material from the supply roll 60 suitably supported on the frame 50 members 61 directly above the reel. In order to wind on the supply of wrapping material, the clutch 29 is disconnected and the end of the strip 52 from the supply roll applied on the side of the reel as indicated by the dotted lines in Figure 8. 55 With the starting of the motor 16, the reel is rotated until a sufficient amount of the wrapping material has been accumulated, whereupon the material may be torn and the loose end secured by a dab of asphalt or other convenient means. 60 In applying the wrapping material to the pipe, the inner end of the roll on the reel is placed about one of the rollers 43 as best shown in Figure 8 and started about the pipe by hand. The roller 43a about which the strip passes is preferably a little larger than the other rollers, and a spring held lever 62 is provided with a shoe 63 arranged to bear against the strip as it passes around the roller to maintain a certain degree of tension upon the strip. This is particularly 65 desirable as the end of the strip approaches and the resistance to movement of the roll on the reel decreases.

70 The angular relation of the reel to the pipe is determined by the ratio between the rotational speed of the reel and the speed of forward move-

ment of the main frame along the pipe; and this ratio, the angular adjustment of the reel and the width of the strip of wrapping material are so arranged and proportioned that the desired amount of lapping of the spiral strip is secured. 5 If desired this lap may be so great that with a single strip, the covering will consist of two or even more thicknesses of material. With the clutch 29 engaged and the other adjustments properly made, the reel is rotated simultaneously 10 with the rotation of the drum 28; and with the progression of the entire machine along the pipe, the wrapping strip is drawn off the inside of the roll 51, the entire roll rotating upon the rollers 15 of the reel.

Means are also provided for applying a second wrapping strip upon the first. The first or main wrapping strip is preferably a felt base material impregnated with a bituminous compound; and under certain conditions it is desirable to 20 overlay this wrapping with a thinner covering of paper. In order to permit this, a secondary reel is mounted on the side of the reel just explained and rotates with it in an orbital path about the pipe. This secondary reel comprises a frame 66, 25 removably secured upon the outer annular plate 42 of the main reel. A roll 67 of wrapping material or strip 68 is journaled in the frame, and the strip passes over a guide roller 69 and under a shoe 70 pressed by the spring 71 so that tension upon the strip is maintained. Of course the space about a pipe line provided by ditching is necessarily quite limited and therefore the thicker and more bulky wrapping material 52 is wound upon its reel in a roll surrounding the 30 pipe. However for thin wrapping material, it is practicable to mount the roll on a reel for orbital rotation about the pipe in the manner just described. In order to make the insertion of the rolls 67 easy, the material is wound upon a mandrel 72 having cone recesses adapted to set between the cone centers 73, one of which is fixed and the other of which is arranged on the spring 35 pressed shaft 74 slidably disposed within the hollow lug 76 fixed on the frame 66. The secondary light wrapping strip is started by hand about the pipe on which the heavy first wrapping is already begun; and as the reels rotate, the light strip is applied in a spiral wrapping over the 40 underlying heavy strip. 45

50 Means are also provided for applying a sealing fluid to the pipe and first heavy wrapping strip while the latter is being applied and preferably this fluid is hot asphalt so that the strip is not only cemented into place but all joints sealed 55 with a decay-resisting and waterproof material. Fixed on the arms 39 between the rotor 34 and the reel 42-43-46 is an annular trough-like chamber 77 best shown in Figures 5 and 6. The chamber has a U-shaped section and is closed at its outer periphery by a rim 78, suitably supported upon the main frame 2. The rim is provided with recesses adapted to hold electric heating elements 79, supplied thru the conductors 80 connected to any suitable source of energy, so 60 that the contents of the chamber may be kept hot. The rim is preferably provided with insulation 81 to prevent waste of heat, and this is 65 retained in place by a metallic shell 82.

70 The chamber is fed thru the pipe 83, connecting the rim with the tank 84, in which fluid asphalt is placed from time to time as the wrapping proceeds. Both the rim and the chamber are made in sections as shown in Figure 5 to permit them to be assembled over the pipe. The 75

rim is conveniently made in two halves, joined together by the readily released swing screws 86 and the lower part is supplied with a drain opening normally closed by the plug 87, so that the chamber may be drained of fluid when it is necessary to disconnect the parts. The removable portion of the annular chamber 77 preferably constitutes about one-third of the circumference of the chamber as shown in Figure 5, and the parts are held together by readily operated swing screws 88.

Extending from the side of the distributor head thus constituted and positioned just ahead of the wrapping strip, is a pipe or distributor 91 having a slot 92 in the end thereof in such position as to discharge a flat jet of the heated sealing fluid directly between the pipe and the wrapping strip. The distributor rotates with a lunar motion about the pipe and the sealing fluid is applied just in front of the strip as it is wound upon the pipe. This avoids cooling and thickening of the sealing fluid and contributes to a tight and even wrapping. Usually enough sealing fluid appears on the surface of the first heavy wrapping to hold the light secondary wrapping in place, if the latter is applied, but if desired the distributor pipe may extend out far enough to apply sealing fluid directly between the secondary strip and the first covering.

30 I claim:

1. A pipe wrapping machine comprising a reel for holding the wrapping material in a roll encircling the pipe, and means for mounting the reel with its axis at a selected angular relation 35 with the axis of the pipe.

2. A pipe wrapping machine comprising a reel for holding the wrapping material in a roll encircling the pipe, means for mounting the reel with its axis at a selected angular relation with 40 the axis of the pipe, and means for rotating the reel to apply the wrapping material to the pipe.

3. A pipe wrapping machine comprising a reel for holding the wrapping material in a roll encircling the pipe, means for mounting the reel with its axis at a selected angular relation with 45 the axis of the pipe, means for rotating the reel to apply the wrapping material to the pipe, and means for moving the reel along the pipe.

4. A pipe wrapping machine comprising a reel 50 for holding the wrapping material in a roll encircling the pipe, means for mounting the reel with its axis at a selected angular relation with the axis of the pipe, means for rotating the reel to apply the wrapping material to the pipe, means for moving the reel along the pipe, and means for 55 variably adjusting the ratio between the speed of rotation of the reel and the speed of progression along the pipe.

5. A pipe wrapping machine comprising a reel 60 for holding the wrapping material in a roll encircling the pipe, means for rotating the reel to apply the wrapping material to the pipe, and means for applying a fluid to bind the wrapping material to the pipe.

6. A pipe wrapping machine comprising a reel 65 for holding the wrapping material in a roll encircling the pipe, means for rotating the reel to apply the wrapping material to the pipe, means for moving the reel along the pipe at a speed bearing a selected ratio to the speed of rotation 70 of the reel, and means for discharging a fluid between the wrapping material and the pipe.

7. In a pipe wrapping machine, a plurality of 75 rollers circumferentially journaled about the pipe and adapted to hold a roll of wrapping material,

means for bodily rotating the rollers about the pipe to transfer the wrapping material from the rollers to the pipe, and means for advancing the rollers along the pipe.

8. In a pipe wrapping machine, a plurality of 5 rollers circumferentially journaled about the pipe and adapted to hold a roll of wrapping material, means for bodily rotating the rollers about the pipe to transfer the wrapping material from the rollers to the pipe, means for advancing the rollers 10 along the pipe, and means for applying a fluid between the wrapping material and the pipe.

9. In a pipe wrapping machine, a reel frame 15 adapted to encircle the pipe, a plurality of rollers journaled circumferentially in said frame to hold a roll of wrapping material, means for rotating said frame to wind the wrapping material upon the pipe, and means for advancing the frame along the pipe.

10. In a pipe wrapping machine, a reel frame 20 adapted to encircle the pipe, a plurality of rollers journaled circumferentially in said frame to hold a roll of wrapping material, means for rotating said frame to wind the wrapping material upon the pipe, means for advancing the frame along the 25 pipe, and means for mounting the frame at a selected angular relation with the pipe.

11. In a pipe wrapping machine, a reel frame 30 adapted to encircle the pipe, a plurality of rollers journaled circumferentially in said frame to hold a roll of wrapping material, means for rotating said frame to wind the wrapping material upon the pipe, means for advancing the frame along the pipe, and means for applying a fluid between 35 the wrapping material and the pipe.

12. In a pipe wrapping machine, a reel frame adapted to encircle the pipe, a plurality of rollers journaled circumferentially in said frame to hold a roll of wrapping material, means for rotating said frame to wind the wrapping material upon 40 the pipe, and a secondary frame arranged on one side of the reel frame to carry a roll of wrapping material in orbital rotation about the pipe.

13. A pipe wrapping machine comprising a reel 45 for holding the wrapping material in a roll encircling the pipe, means for rotating the reel to apply the wrapping material to the pipe, and means for applying a fluid to the pipe and wrapping material.

14. A pipe wrapping machine comprising a reel 50 for holding the wrapping material in a roll encircling the pipe, means for rotating the reel to apply the wrapping material to the pipe, means for applying a fluid to the pipe and wrapping material, and means for heating the fluid. 55

15. A pipe wrapping machine comprising a reel for holding the wrapping material in a roll encircling the pipe, means for rotating the reel to apply the wrapping material to the pipe, a chamber for fluid adjacent the reel, means for heating 60 the chamber and means for discharging the heated fluid upon the pipe and wrapping material.

16. In a pipe wrapping machine, a rotor adapted to encircle the pipe, a reel for holding the wrapping material in a roll encircling the pipe and connected for rotation with said rotor, means for rotating the rotor, and means for moving the rotor along the pipe. 65

17. In a pipe wrapping machine, a rotor adapted to encircle the pipe, a reel for holding the wrapping material in a roll encircling the pipe and connected to rotate with said rotor, means for rotating the rotor, means for moving the rotor along the pipe, a fluid distributor mounted for 70

75 a roll of wrapping material, and means for applying a fluid to the pipe and wrapping material.

- rotation with said rotor, and means for supplying the distributor with fluid.
18. In a pipe wrapping machine, a rotor adapted to encircle the pipe, a reel for holding the wrapping material in a roll encircling the pipe and connected to rotate with said rotor, means for rotating the rotor, means for moving the rotor along the pipe, an annular reservoir mounted for rotation with the rotor, and a fluid distributor for discharging fluid from the reservoir upon the pipe and wrapping material.
19. In a pipe wrapping machine, a rotor adapted to encircle the pipe, a reel for holding the wrapping material in a roll encircling the pipe and connected to rotate with said rotor, means for rotating the rotor, means for moving the rotor along the pipe, a non-rotative rim, an annular reservoir journaled within the rim for rotation with the rotor, a fluid distributor fixed on the reservoir, and a supply conduit connected to the reservoir thru the rim.
20. In a pipe wrapping machine, a rotor adapted to encircle the pipe, a reel for holding the wrapping material in a roll encircling the pipe and mounted for rotation with said rotor, means for rotating the rotor, and means for varying the angular relation between the reel and the pipe.
21. In a pipe wrapping machine, a rotor adapted to encircle the pipe, a reel for holding the wrapping material in a roll encircling the pipe and mounted for rotation with said rotor, means for rotating the rotor, means for moving the rotor along the pipe, and means for varying the angular relation between the reel and the pipe.
22. In a machine for wrapping objects, a reel comprising a frame, a series of rollers circumferentially journaled in said frame, and an annular plate forming a flange for the series of rollers and journaled at the side thereof.
23. In a machine for wrapping objects, a reel comprising a frame, a series of rollers circumferentially journaled in said frame and each provided with an annular groove, and a flange for the series of rollers comprising a ring journaled in said roller grooves.
24. In a machine for wrapping objects, a rotor adapted to encircle the object, a pair of arms extending from the rotor, a frame pivotally mounted on said arms, and a series of rollers circumferentially journaled in said frame for holding the wrapping material in a roll surrounding the object.
25. In a machine for wrapping objects, a rotor adapted to encircle the object, a pair of arms extending from the rotor, a frame pivotally mounted on said arms, a series of rollers circumferentially journaled in said frame for holding the wrapping material in a roll surrounding the object, and means for rotating the rotor.
26. In a machine for wrapping objects, a rotor adapted to encircle the object, a pair of arms extending from the rotor, a frame pivotally mounted on said arms, a series of rollers circumferentially journaled in said frame for holding the wrapping material in a roll surrounding the object, means for rotating the rotor and means for advancing the rotor along the pipe.
27. A pipe wrapping machine comprising a frame, a reel for holding the wrapping material arranged on the frame, a drum, a cable on the drum and adapted to be secured to a fixed object, power means for simultaneously driving the reel to wrap the material about the pipe and driving the drum to move the frame along the pipe, and a speed-change device interposed between the power means and one of its driven means to vary the ratio of speeds therebetween.
28. In a pipe wrapping machine, a rotor adapted to encircle the pipe, a reel for holding the wrapping material in a roll encircling the pipe and mounted for rotation with said rotor, means for rotating the rotor, and friction-reducing means on the reel to facilitate movement of the roll thereon.
29. In a pipe wrapping machine, a rotor adapted to encircle the pipe, a reel for holding the wrapping material in a roll encircling the pipe and mounted for rotation with said rotor, means for rotating the rotor, means for moving the rotor along the pipe, an annular reservoir mounted for rotation with the rotor, a fluid distributor for discharging fluid from the reservoir upon the pipe and wrapping material, and means for heating the fluid in said reservoir.
30. In a pipe wrapping machine, a rotor adapted to encircle the pipe, a reel for holding the wrapping material in a roll encircling the pipe and mounted for rotation with said rotor, means for rotating the rotor, means for moving the rotor along the pipe, a non-rotative rim, an annular reservoir journaled within the rim for rotation with the rotor, a fluid distributor fixed on the reservoir, and heating means disposed in said rim.
31. A pipe wrapping machine comprising a frame including a reel for holding wrapping material in a roll encircling the pipe, a secondary reel for holding a roll of wrapping material at one side of the pipe and mounted on the frame, and means for rotating the frame to transfer the wrapping material from each reel to the pipe.
32. A pipe wrapping machine comprising a frame including a reel for holding wrapping material in a roll encircling the pipe, a secondary reel for holding a roll of wrapping material at one side of the pipe and mounted on the frame, means for rotating the frame to transfer the wrapping material from each reel to the pipe, and means for moving the frame along the pipe.
33. A pipe wrapping machine comprising a frame including a reel for holding wrapping material in a roll encircling the pipe, a secondary reel for holding a roll of wrapping material at one side of the pipe and mounted on the frame, means for rotating the frame to transfer the wrapping material from each reel to the pipe, and means for changing the angular relation of the frame to the pipe.
34. A pipe wrapping machine comprising a frame including a reel for holding wrapping material in a roll encircling the pipe, a secondary reel for holding a roll of wrapping material at one side of the pipe and mounted on the frame, means for rotating the frame to transfer the wrapping material from each reel to the pipe, means for moving the frame along the pipe, and means for changing the angular relation of the frame to the pipe.
35. A pipe wrapping machine comprising a main frame, an annular rotor adapted to encircle the pipe and journaled on said frame, a pair of arms extending from the rotor, a reel pivotally mounted in said arms for holding the wrapping material in a roll encircling the pipe, and means on the frame for rotating the rotor and simultaneously advancing the frame along the pipe.
36. A pipe wrapping machine comprising a main frame, an annular rotor adapted to encircle the pipe and journaled on said frame, a reel for hold-

5 ing the wrapping material in a roll encircling the pipe and pivotally mounted on said rotor, and means on the frame for rotating the rotor and simultaneously advancing the frame along the pipe.

37. A pipe wrapping machine comprising a main frame, an annular rotor adapted to encircle the pipe and journaled on said frame, a reel for holding the wrapping material in a roll encircling the 10 pipe and pivotally mounted on said rotor, means on the frame for rotating the rotor and simultaneously advancing the frame along the pipe, and means for discharging a fluid between the wrapping material and the pipe.

15 38. A pipe wrapping machine comprising a reel for holding the wrapping material in a roll encircling the pipe, means for rotating the reel to apply the wrapping material to the pipe, and means for moving the reel along the pipe.

20 39. The method of wrapping a pipe which comprises forming a roll of wrapping material encircling the pipe, placing the inner end of the roll on the pipe, and then rotating the roll and advancing it axially of the pipe to lay the wrapping material in spirals about the pipe.

25 40. A pipe wrapping machine comprising a rotor adapted to encircle the pipe, means mounted on said rotor for holding the wrapping material, means for rotating the rotor to transfer the wrapping material from the holding means to the pipe, means including a rotatable member for moving the rotor along the pipe, means for varying the relative speed of rotation between the rotatable member and rotor, and means for applying a fluid to bind the wrapping material to the pipe.

30 41. A pipe wrapping machine comprising a reel for holding the wrapping material in a roll encircling the pipe, means including a rotatable member for moving the reel along the pipe, means for rotating the reel to apply the wrapping material to the pipe, and means for varying the relative speed of rotation between the rotatable member and reel.

35 42. A pipe wrapping machine comprising a reel for holding the wrapping material in a roll encircling the pipe, means including a rotatable member for moving the reel along the pipe, means for rotating the reel to apply the wrapping material to the pipe, and means for varying the speed of rotation of the rotatable member to vary the speed of movement of the reel along the pipe.

40 43. A pipe wrapping machine comprising a reel for holding the wrapping material in a roll encircling the pipe, means including a rotatable member for moving the reel along the pipe, means for rotating the reel to apply the wrapping material to the pipe, means for varying the relative speed of rotation between the rotatable member and reel, and means for applying a fluid to bind the wrapping material to the pipe.

45 44. A pipe wrapping machine comprising a reel for holding the wrapping material in a roll encircling the pipe, positive means for rotating the reel to apply the wrapping material to the pipe, and means for moving the reel axially along the pipe.

50 45. In a pipe wrapping machine, a reel for holding the wrapping material in a roll encircling the pipe, and means for mounting the reel with its axis at selected angular relation with the axis of the pipe.

55 46. In a pipe wrapping machine, a reel for holding the wrapping material in a roll encircling the pipe, means for mounting the reel with its axis at selected angular relation with the axis of the pipe, and means for moving the reel along the pipe.

60 47. In a pipe wrapping machine, a reel for holding the wrapping material in a roll encircling the pipe, means for mounting the reel with its axis at selected angular relation with the axis of the pipe, and means for effecting relative movement between the reel and the pipe.

65 48. A pipe wrapping machine including a frame, means to move said frame along the pipe as a support, a roll of wrapping material, means to carry said roll spirally about said pipe, and means to apply a coating to said wrapping material after the pipe has been wrapped.

70 49. A pipe wrapping machine comprising a carriage, wheels supporting the carriage on the pipe for movement longitudinally of the pipe, a drum mounted at the rear of the carriage to rotate about an axis approximately coincident with the axis of the pipe for spirally winding a band of material on the pipe in the rear of the wheels, and means on the carriage for applying a liquid coating to both sides of the wrapping material.

75 50. A pipe wrapping machine comprising a rotor adapted to surround the pipe, means mounting the rotor for movement along the pipe as a track, a reel for holding wrapping material in a roll positioned bodily alongside the pipe and arranged with one end adjacent the rotor and the other end spaced therefrom, and means projecting from the rotor and extending alongside the roll for supporting the outer end of the reel.

80 51. A pipe wrapping machine comprising a rotor adapted to surround the pipe, means mounting the rotor for movement along the pipe as a track, a reel for holding wrapping material in a roll positioned bodily alongside the pipe and arranged with one end adjacent the rotor and the other end spaced therefrom, and a yoke frame projecting outwardly from the rotor and embracing the roll for supporting each end of said reel.

85 52. A pipe wrapping machine comprising a reel for holding wrapping material in a roll positioned bodily alongside the pipe, a rotor adapted to surround the pipe and positioned entirely to one side of the reel, means projecting from the rotor for supporting both ends of the reel, and means mounting the rotor for movement along the pipe as a track.

90 53. A pipe wrapping machine for an installed pipe line, comprising a rotor completely encircling the pipe, means mounting the rotor for movement along the pipe as a track, said rotor having a section movable relative thereto whereby the rotor may be assembled about the pipe line, a reel for holding a supply roll of sheet wrapping material bodily alongside the pipe, a journal for the reel having support on one of said rotor sections, means for fastening the rotor sections together whereby the latter may be disconnected and the rotor assembled about the pipe without demounting the supply roll, said journal projecting outwardly from the rotor, and means for supporting the outer end of said journal.
